SEWING MACHINE

Arnljot Austlid, Oslo, Norway

Application January 18, 1947, Serial No. 722,814
In Norway January 22, 1946

5 Claims. (Cl. 112—159)

1

This invention relates to sewing machines adapted for making zig-zag-seams.

The machine in question is of the type in which the needle bar and the looper shaft thereof are interconnected by a displaceable bail or the like adapted to be reciprocated in the longitudinal direction of the machine, thus transferring the same movements to the needle bar and to the looper shaft, whereby zigzag-seams may be made.

It is an object of the invention to provide for such interconnection of the needle bar, the bail and the looper shaft that said bar and shaft will be displaced absolutely in unison in the longitudinal direction of the machine.

Another object is to provide a simple but effective driving arrangement for said bail, which arrangement is adjustable in a simple manner, so as to set the bail for zigzag-seams of different widths or for usual straight seam if desired.

Other features of the invention are disclosed in and by the following description.

The annexed drawing illustrates an embodiment of the invention, where only those parts of the machine which relate to the invention are shown.

Figure 1 is a side view of a sewing machine according to the invention, part of the front being broken away, to show certain features of the mechanism.

Figure 2 is an end view of the same, also with a part broken away.

Figure 3 shows, on a larger scale, a detail of the mechanism.

The sewing machine body consists of the arm 1 with head and supporting standard, and of the base plate 2 of channel-formed section. Within the base plate is journalled a looper shaft 4, driven by a motor or in other suitable manner, and carrying a looper 5, which is located beneath the needle bar 3 and cooperates with the needle. When the machine is to be used for sewing zig-zag-seams the needle bar 3 and the looper shaft 4 with its looper 5 must reciprocate synchronously in the longitudinal direction of the machine, and the needle must be moved down into the fabric each time the needle bar and the looper are at one of the end positions of their reciprocating movements.

Intercoupling of needle bar and looper shaft is obtained by means of a bail 6, reciprocally housed in the machine arm 1. At one end of said bail is directly journalled the needle bar 3, and the other end of the bail directly carries the looper shaft 5, which is rotatable but not displaceable

2

therein. More specifically, the bail 6 has an enlarged end portion 6' in which the needle bar 3 is slidably mounted for vertical movement. The drive means for reciprocating the needle bar vertically is omitted as superfluous, being understood in the art, and forming no actual part of the invention. On the other hand, the downwardly projecting portion 6'' of bail 6 may be provided with a hole in which looper shaft 4 is rotatably mounted, thus the bail and looper shaft are movably connected together and associated. In order to prevent undesired axial movement of this looper shaft relatively to the bail, the bail portion 6'' is located between two shoulders or flanges 29 fixed on the looper shaft. Thus, when the bail 6 is reciprocated in the longitudinal direction of the machine, the needle bar and the looper shaft both must move exactly in the same manner.

20 The bail 6 receives its reciprocating movement from a crank 8 on a shaft 7 rotated by the machine's driving mechanism. The latter includes the gear 25 which meshes with and is driven by pinion 26 on the end of looper shaft 4. The length of pinion 26 is, of course selected to be sufficient to allow the pinion to slide along in parallelism to the axis of gear 25 during longitudinal displacement of looper shaft 4. In order to facilitate axial movement of the looper shaft, 30 the rotor of the driving motor 27 is axially movable a short distance corresponding to the extent of the axial movement of the mentioned looper shaft which is secured to the rotor. The connecting rod 9 of the crank is pivotally attached to an arm 11, between the ends thereof, by means of a pin 10. At one end thereof said arm 11 is by means of a pin 12 pivoted on the vertical part of the bail 6, and the other end of arm 11 carries a follower roller 13, engaged in 35 a cam groove 14 provided in a guide member 15, which for instance may be cylindrical. This guide member 15 is secured to a shaft 16, which may be adjusted into different angular positions by means of an arm 17, whereby the groove 14 may be set in different angular positions.

40 The arrangement described operates as follows: When the crank 8 rotates the follower roller 13 is displaced in and guided by the cam groove 14, and if the latter is set in an oblique or sloping position, for instance as shown in Figure 1, roller 13 must reciprocate a little in horizontal direction, arm 11 simultaneously being raised and lowered, swinging on its pivot 12. This reciprocating movement of roller 13 is, through arm 11 45 and pivot 12, transferred to the bail 6, which

latter thereby causes the needle bar and the looper shaft to reciprocate accordingly. By turning shaft 16 by means of arm 17 the guide member 15 with groove 14 may be set in any desired angular position, thus adjusting the extent of the reciprocating movement and thereby the width of the zigzag-seam. When groove 14 is set in vertical position no reciprocating movement of bail 6 occurs, and the machine will sew an ordinary, straight seam. In order that no movement at all shall be imparted to bail 6 when the groove is in this position, the major intermediate portion of the groove is formed with a circular curve having its center of curvature in the axis of pivot 12, the roller 13 then exerting no pressure on the walls of the groove when arm 11 is raised and lowered.

In order to enable the seam to be shifted to the right or to the left without shifting the piece of fabric, shaft 16 is eccentrically journalled in a sleeve 18, which latter is rotatably supported in the front material of the machine body and adapted to be set in different angular positions by means of an arm 20. Turning of sleeve 18 causes shifting of shaft 16 and thus also of guide member 15 towards the left or towards the right, and such shifting is, through arm 11 and bail 6, transferred to the needle bar and to the looper shaft.

Figure 3 shows a section through the guide member 15 with groove 14 and the roller 13, on a larger scale.

The fabric mover or feeder 21 is driven from a shaft 22. Said shaft carries two eccentric portions 23 and 24 respectively, which are coupled to the fabric mover by means of arms, so that the fabric mover receives a vertical and also a horizontal reciprocating movement. Control of the stitch-length and also reversion of the direction of movement of the fabric is effected by means of a controlling arm, in a manner known per se. However, in accordance with the invention said control mechanism is so arranged, that the fabric mover is automatically lowered if the stitch-length is adjusted to become zero, and is again raised if the stitch-length is increased.

Preferably the looper shaft 4 is provided with an extension 28 penetrating the material of the machine body and adapted for attachment of a pool member when thread should be spooled.

The constructional details of the arrangement shown may be widely modified and varied within the scope of the invention.

I claim:

1. In a zig-zag stitch forming sewing machine comprising a base; a machine body on said base; and a horizontal looper shaft mounted in said base for reciprocation in a horizontal direction, the combination of a needle bar arranged partly within the machine body and depending toward said base; an elongated bail located within said machine body having an integral depending portion projecting into said base and mounted for horizontal reciprocation; an enlarged end portion upon the elongated bail in which the needle bar is slidably mounted for vertical movement, the depending portion of said bail having a bearing hole for supporting said looper shaft in order to allow the latter to extend through said bail; means upon said looper shaft engaging with said bail at both ends of the bearing hole therein for preventing axial displacement of said looper shaft with respect to said bail; and operating means for reciprocating said bail in the horizontal di-

rection and thereby oscillating the bail together with said needle bar and said looper shaft.

2. In a zig-zag stitch forming sewing machine comprising a base; a substantially L-shaped hollow machine body having a longer horizontally extending body portion and a relatively shorter vertically extending body portion, the combination of a looper shaft mounted in said base reciprocably in a horizontal direction parallel to the longer body portion of said L-shaped machine body; a needle bar slidably mounted for vertical movement at the free end of said horizontally extending longer body portion of said L-shaped machine body; a substantially elongated bail having a longer bail portion and a relatively shorter bail portion, said bail being so disposed within said machine body that said longer bail portion is located within said longer body portion and said shorter bail portion is located within said short body portion and depending into said base; means including an enlarged free end portion upon the longer bail portion for supporting the needle bar for vertical sliding movement, the short end of said bail having a bearing hole through which the looper shaft extends means upon said looper shaft engaging with said bail at both ends of the bearing hole therein for preventing axial displacement of said looper shaft with respect to said bail; and means for reciprocating said L-shaped bail in a horizontal direction and thereby oscillating the bail together with said needle bar and said looper shaft.

3. In a zig-zag stitch forming sewing machine comprising a base; a machine body on said base; a horizontal looper shaft mounted in said base for reciprocation in a horizontal direction, the combination of a needle bar arranged partly within the machine body and depending toward said base; an elongated bail located within said machine body having an integral depending portion projecting into said base and mounted for horizontal reciprocation; an enlarged end portion upon the elongated bail in which the needle bar is slidably mounted for vertical movement, the depending portion of said bail having a bearing hole for supporting said looper shaft in order to allow the latter to extend through said bail; means upon said looper shaft engaging with said bail at both ends of the bearing hole therein for preventing axial displacement of said looper shaft with respect to said bail; and operating means for reciprocating said bail in the horizontal direction and thereby oscillating the bail together with said needle bar and said looper shaft; said operating means including an arm disposed transversely of the depending portion of said bail; an angularly adjustable guide member; a crank with a connecting rod pivotally connected to the intermediate portion of said arm and the latter 45 arm at the ends thereof being respectively pivotally connected to said bail and operatively in contact with said angularly adjustable guide member, the guide member having guide means of such construction for guiding said arm that horizontal movements are transferred to said arm and to the bail upon rotation of said crank.

4. In a zig-zag stitch forming sewing machine comprising a base; a machine body on said base; a horizontal looper shaft mounted on said base for reciprocation in horizontal direction, the combination of a needle bar arranged partly within the machine body and depending toward said base; an elongated bail located within said machine body having an integral depending portion projecting into said base and mounted for hori-

zontal reciprocation; an enlarged end portion upon the elongated bail in which the needle bar is slidably mounted for vertical movement, the depending portion of said bail having a bearing hole for supporting said looper shaft in order to allow the latter to extend through said bail; means upon said looper shaft engaging with said bail at both ends of the bearing hole therein for preventing axial displacement of said looper shaft with respect to said bail and operating means for reciprocating said bail in the horizontal direction and thereby oscillating the bail together with said needle bar and said looper shaft; said operating means including an arm disposed transversely of the depending portion of said bail; an angularly adjustable guide member; a crank with a connecting rod pivotally connected to the intermediate portion of said arm and the latter arm at one end thereof operatively engaging with said bail, the angularly adjustable guide member having a curvilinear cam groove; and a follower rotatably mounted at the other end of said arm and engaging in said curvilinear cam groove, at least the major intermediate portion of the curvilinear cam groove having a radius substantially equal to the length of said arm.

5. In a zig-zag stitch-forming sewing machine comprising a base; a machine body on said base; and a horizontal looper shaft mounted on said base for reciprocation in horizontal direction, the combination of a needle bar arranged partly within the machine body and depending toward said base; an elongated bail located within said machine body having an integral depending portion projecting into said base and mounted for horizontal reciprocation; an enlarged end portion upon the elongated bail in which the needle bar is slidably mounted for vertical movement, the depending portion of said bail having a bearing hole for supporting said looper shaft in order to allow the latter to extend through said bail;

means upon said looper shaft engaging with said bail at both ends of the bearing hole therein for preventing axial displacement of said looper shaft with respect to said bail; and operating means for reciprocating said bail in horizontal direction and thereby oscillating the bail together with said needle bar and said looper shaft, said operating means including an arm disposed transversely of the depending portion of said bail; an angularly adjustable guide member, a crank with a connecting rod pivotally connected to the intermediate portion of said arm and the latter arm at one end thereof operatively engaging with said bail, the angularly adjustable guide member having a curvilinear cam groove; a follower roller rotatably mounted at the other end of said arm and engaging in said curvilinear cam groove, at least the major intermediate portion of the curvilinear cam groove having a radius substantially equal to the length of said arm; a rotatably adjustable sleeve mounted in said machine body and having an eccentric bearing hole therein; and a shaft rotatably mounted in the eccentric bearing hole in said rotatably adjustable sleeve and rigidly secured at one end thereof to said guide member.
